UNITED STATES PATENT OFFICE.

JOHN CUNINGHAM, OF MANITO, ILLINOIS.

END-GATE.

SPECIFICATION forming part of Letters Patent No. 381,057, dated April 10, 1888.

Application filed January 4, 1888. Serial No. 250,769. (No model.)

To all whom it may concern:

Be it known that I, JOHN CUNINGHAM, a citizen of the United States, residing at Manito, in the county of Mason and State of Illinois, 5 have invented a new and useful Improvement in Scoop-Boards and End-Gates, of which the following is a specification.

The invention is a combined end-gate and chute or scoop-board for use in hauling corn, 10 vegetables, coal, and other materials; and it consists in the construction and novel combination of parts hereinafter described, and pointed out in the appended claim.

In the accompanying drawings, Figure 1 represents a perspective view of the end of a wagon having the device attached. Fig. 2 represents a side view of the same with the gate closed. Fig. 3 represents a longitudinal section of Fig. 1.

Referring to the drawings by letter, A designates the end of a wagon-body having the eye-bolts or staples B and C attached to each side.

D' are bearing-brackets extending rearwardly from the ends of the cross-bar d, secured transversely to the bottom of the wagon adjoining its ends, and having the upwardly-extended bearing-loops d', the upper ends of which extend slightly inward toward the wagon. The said brackets are made of strap- 30 iron, and have their flat ends d² secured to the extended ends of the cross-bar d by suitable bolts, d³, and nuts engaging the tapped lower ends thereof, the bearing-loop being formed at the middle portion of each, as shown.

E is the combined end-gate and chute, somewhat longer than the sides of the wagon are high and provided with side-boards e, which stand upward when the end-gate is lowered to form a chute. The wider inner ends of the 40 side-boards rest, when the gate is raised, on the floor of the wagon.

F is the journal-bar of the end-gate, secured by the straps f and suitable bolts to the side-boards e, the said straps passing through suitable openings in the bottom of the end-board and having their outer ends rounded and threaded and engaged to nuts outside of the journal-bar, the ends of which are rounded and engaged in the bearing-loops d'. The front or 45 upper edge, f', of the bottom of the end-gate is rounded and turns and lifts on the rounded upper edge, g, of the end of the floor of the

wagon-body, when the end-gate is turned up so that the journals of the bar F are lifted in the loops of the bearing-brackets. Thus the lower 55 or inner ends of the side-boards e are caused to bind on the floor of the wagon and maintain the end-gate closed should the fastening devices, hereinafter described, become disconnected.

G are the vertical ways secured to the inner sides of the wagon-body at its end to receive the ordinary end-gate fitting therein. When the combined end-gate and chute is used, the ordinary end-gate is removed, the combined 65 end-gate and chute fitting between the ways.

It is evident that should it be necessary to use the ordinary end-gate the bearing-brackets can be unbolted from the cross-bar d and the combined end-gate and chute detached therefrom.

H is a brace-bar extending across the interior of the wagon-body with its hooked ends engaged in staples or eyebolts h, secured to the sides of the body in front of the end-gate when 75 raised. The purpose of this brace-bar is to brace the wagon-box.

I I are rods pivoted or swiveled upon the ends of the transverse bar i, secured to the outer free end of the end-gate. The said rods 80 have their free ends hooked at J to engage either the staples B or C on each side of the wagon-body. The hooks J engage the staples B when the gate E is closed or raised, closing the end of the wagon-body, and the said rods 85 and staples then maintain the gate in its elevated position. When the gate is lowered, it is held in position, inclining slightly upward from the end of the wagon by engaging the hook J in the staples C. The end-gate can then 90 act as a chute or inclined plane to quickly load or unload the wagon. When dumping, the end-gate may be lowered, as described, have part of the load shoved thereon, and may be then entirely lowered by disengaging the hooks 95 J from the staples C, thus depositing its load quickly in the desired spot. When the end-gate is turned down, the side-boards prevent the load from falling off at the sides. The end-board constructed as described makes a very 100 convenient, simple, and useful attachment to a wagon for loading and unloading the same.

Having described my invention, I claim—
The combination of the wagon-body having

the upper edge of its rear end made convex, the cross-bar d , secured to the bottom of the body at its rear end and projecting beyond the sides thereof, the bearing-brackets formed from 5 a single metallic strap having its middle portion doubled on itself to form the upward and inward extending loops d' , and having their flat ends brought together and rested on the ends of the cross-bar d , the bolts inserted 10 vertically through said ends d^2 and the cross-bar, the end-gate having its upper inner edge made convex, the cross-bar F , secured to the

end-gate and having its ends playing in the loops d' , and means for holding the end-gate in its raised and lowered positions, substantially as specified. 15

In testimony that I claim the foregoing as my own I have hereto affixed my signature in presence of two witnesses.

JOHN CUNINGHAM.
